his Atty.

UNITED STATES PATENT OFFICE

ARTHUR SOLL, OF COMPTON, CALIFORNIA, ASSIGNOR OF THIRTY-SEVEN AND ONE-HALF PER CENT TO LEWIS A. LARSON AND TWENTY-FIVE PER CENT TO SAMPSON C. BEVEE, BOTH OF BURLEY, IDAHO

TELESCOPING CORE-DRILL

Application filed April 11, 1931. Serial No. 529,324.

This invention relates to devices used for taking material out of the ground in form of a solid or in as undisturbed a condition as possible, commonly referred to as a core with-
5 in the tool taking the material.

One of the objects of this invention is to provide a core-taking barrel within the tool designed so that the core-material taken by the tool may be held and maintained in a
10 possibly continuous and undisturbed condition.

Another object is to provide means whereby the taken material may be advanced into the tool in such a condition even though the
15 material be of a character that would show a tendency to collapse if not so held.

Another object is to provide means whereby a clogging up of the tool can be avoided even though the taken material has the tendency to collapse.

Other objects will appear from the following description and appended claims as well as from the accompanying drawing, in which—

25 Fig. 1 is a fragmentary longitudinal mid-sectional view of a core-drill provided with a retainer designed to operate according to this invention.

Fig. 2 is an enlarged fragmentary detail
30 section of a frictional interengagement between adjoining tube members.

So-called core-taking is practiced for various reasons, in well-drilling, earth-boring, by the oil industry as well as by others, principally, however, to disclose the strata of different formations in the ground, in the natural, or chronological, or continuous and undisturbed order in which such formations are contained or embedded in the earth.

40 However, though certain layers of certain formations form a rigid or firm mass from which a suitable portion may work itself in form of a core into a drilling tool, other formations are not in such firm layers, or at least have a tendency to break up into smaller pieces that may clog up the inside of the drilling tool instead of slipping further and further into the drilling tool as the tool is forced into the ground.

50 On the other hand, inasmuch as a core be-

comes more desirable the deeper the strata is disposed from which samples could give information, and, since a drilling may extend several thousand feet below the surface, it stands to reason that it cannot always be positively ascertained whether the inside of the tool is becoming clogged up, notwithstanding the fact that some drillers claim to be able to feel any functioning of the tool in the ground by a touch of the working rod extending above the ground, before serious trouble is encountered, or at least the core-material in the tool is milled about to such an extent that its value as a core for the purpose for which it is wanted is rather doubtful.

As illustrated, a series of comparatively thin and light tube members 3 are telescopically mounted within the drilling tool 4, which may be of the customary strong and heavy design, with a cutter head 5 at its lowermost termination and a suitably shaped top end 6 adapted to be attached to the working rods or tubes of a well-drilling outfit.

The outermost tube member 3a is suitably engaged to the tool 4, while the innermost tube member 3b is provided with a central head 7 against which any material cored into the drilling tool will abut if solid and thereby free enough to slip into the tubes.

However, whether a solid and coherent core that would serve to push against the head 7, or a crumbling mass of material that would most likely bind against the inner walls of the tubes, any material upon being cored or forced into the several tubes would serve to lift the tubes one after the other within the hollow of the tool 4, and thereby facilitate the taking of a desirably long core or a long stretch of successive strata material.

Moreover, most important of all, any material picked up by or into the drilling tool would be most likely to advance into the tool in the successive order in which various materials were embedded in the earth, as the tool gradually works itself through the strata.

If the cored material is of the crumbling type it most likely will lift each successive tube section as soon as the entering mate-

rial is frictionally sufficiently engaged to the inside walls of any of the tube sections independently of any frictional engagement of the material in any of the other tube sections.

- 5 On the other hand, if the material is firm and sufficiently coherent, the topmost or furthest advanced end of a solid core will abut against the head 7 and thereby lift the several telescoping tube sections one after 10 the other by means of the shouldered engagement 8-9 at the ends of the sections.

When a crumbling strata is encountered, it would perhaps not be advisable to use any rinsing liquid, since by the enormous pressure 15 customarily applied, especially at great depth, a large portion of the cored material would be washed or forced to the surface and out of the core-tool, but, inasmuch as a coring is most commonly only attempted in a 20 comparatively solid strata, the head 7 is provided with apertures 10-11 by which such rinsing liquids can pass through the tool and also through the telescoping tube sections 3.

- 25 On a completion of a coring operation, or at certain or suitable intervals when a lifting of a core becomes desirable, during the lifting of the core with and within the core-tool, while customarily the rinsing liquid is 30 still in the hole, to prevent a back-washing of the core from the core-barrel into the hole, the head 7 is provided with a check-valve 12, whereby the liquid in the bore-hole or well is prevented from entering the core-tool from 35 the top end as the tool is removed from the well.

For guiding the top end of the several tube-sections centrally within the tool 4, barrel-guides 13 are provided.

- 40 Core catching members 14 are provided in the lower end of the coring tool, and also core-guiding members or a core guide 15.

Though it normally is not absolutely essential that the several telescoping tube sections be provided with any further engagements besides those referred to above and indicated at 8-9, for and during certain well-drilling operations it may be desirable to have the additional lightly frictionally engaging indentations 16 provided near the shouldered ends of the tube sections.

Such indentations would require a slight or light jerking force for disengaging one tube section from the other.

- 55 It must be understood that the core-barrel or tube sections 3 are of comparatively thin material while the tool 4 may be considerable heavier, since the barrel is not really subjected to any great strain but merely serves 60 to follow the core advancing gradually into the tool.

Having thus described my invention, I claim:

1. In a core-drill for well drilling operations having a cutter-head at the bottom end 65

and a connection at the upper end by which the drill can be applied to upwardly extending drill tools, a core-barrel made of telescoping sections mounted within the hollow of the drill and adapted to telescopically expand when and as a core advances into the drill. 70

2. In a core-drill, a hollow drill-body of customary heavy type, and a telescoping core-barrel expansibly mounted within the 75 hollow of the said body and adapted to guide and hold a core as it advances into the drill-body.

3. In a core-drill, a hollow drill-body, a 80 telescoped sectioned core-barrel normally disposed in the lower end of the hollow of the drill-body and adapted to telescopically follow any material entering the drill-body with the innermost section of said barrel to come into contact with the entering core 85 first and the succeeding sections to follow in the arranged order.

4. In a core-drill, a hollow drill-body, a 90 telescoped sectioned core-barrel in the drill-body, and a head-member on the innermost section of said barrel adapted to be the first part to contact with any core-material entering the barrel.

5. In a core-drill, a hollow drill-body, a 95 telescoped sectioned core-barrel in the drill-body, a head-member on the innermost section of said barrel and a check-valve in said head adapted to prevent a back-washing of received core-material.

6. In a core-drill, a hollow drill-body, a 100 telescoped sectioned core-barrel in the drill body, and a core-catching member in the lower end of the drill-body.

7. In a core-drill, a hollow drill-body, a 105 telescoped sectioned core-barrel in the drill-body, core-catching means in the lower end of the drill-body, and guiding means in the body for guiding core-material into the telescopically disposed core-barrel in the drill-body. 110

In testimony that I claim the foregoing as my invention I have signed my name.

ARTHUR SOLL.
